UNITED STATES PATENT OFFICE.

JOSEPH F. O'BRIEN, OF NEW YORK, N. Y.

WINDOW CONSTRUCTION.

1,157,031.

Specification of Letters Patent.

Patented Oct. 19, 1915.

Application filed September 16, 1913. Serial No. 790,096.

To all whom it may concern:

Be it known that I, JOSEPH F. O'BRIEN, residing at New York, N. Y., have invented certain new and useful Improvements in 5 Window Construction, of which the following is a specification.

This invention relates to window constructions adapted particularly for use on motor vehicles.

10 The object of this invention is to provide a window construction embodying a sliding sash or glass panel and which is simple in construction, neat in appearance, and is convenient to operate.

15 The invention also has for an object the provision of a construction in which rain will be effectually excluded when the sash is in closed position.

20 The invention is illustrated in the accompanying drawings, in which,—

Figure 1 is a longitudinal section of a door for a limousine. Fig. 2 is a section on the line 2—2 of Fig. 1. Fig. 3 is an enlarged detail section showing a portion of 25 the door frame on the sliding glass panel in a closed position. Fig. 4 is a section on the line 4—4 of Fig. 2.

Referring to the drawings, 10 indicates 30 generally the door frame which is provided with an opening 11, this opening being closed by means of a sash or glass panel 12. The side members of the frame 10 are provided with grooves 13 which are preferably wider adjacent to the middle portion of the 35 length thereof and the outer edges 14 of which are curved or bowed, as shown in Fig. 1.

Arranged in the grooves 13 are guides 15 having longitudinal slots 16 for the glass 40 panel 12. The guides 15 are preferably covered with plush 17, as shown in Fig. 4, to prevent rattling. The guides 15 are secured at one point in their length to the frame 10, preferably at the top, as indicated 45 at 18, and are free to move laterally in the grooves 13 for a purpose to be hereinafter described.

At the lower side of the opening 11 in the frame is arranged a vertically extending bar 50 or ledge 19, and on the lower edge of the panel 12 is a metal plate 20 which is bent into a form having a substantially S-shaped cross section, the portion of this plate which engages the panel 12 being U-shaped, and 55 there being a downwardly turned lip 21 on the

outer side of the sash which is adapted to hook over the ledge 19 and secure the panel in the closed position, and also prevent rain from entering between the panel and the ledge. The metal plate 20 is also provided with hooks 22 adjacent its ends to which flexible supporting wires or cords 23 are adapted to be attached, these cords passing over pulleys 24 which are fixed at the top of the frame and then passing downwardly 60 through slots 25 in the frame to spring counter-balances 26. The spring counter-balances 26 are merely indicated on the drawings, these being a common article of trade and any preferred type of which may be 65 used. It will be seen that by this arrangement the panel 12 will be supported in any position to which it is moved in the guides 15. Suitable handle or finger pieces 27 may be provided on the panel 12 to facilitate 70 moving the same.

As shown in Fig. 1, the panel 12 is free to move up and down in the guides 15, and the metal plate 20 will clear the ledge 19. When it is desired to secure the panel 12 80 in the closed position shown in Fig. 3 it is raised to the proper height and then the lower end thereof is pushed outwardly to engage the lip 21 with the ledge 19, in this position, the guides 15 fitting the edge 14 85 of the grooves in the frame 10 and making a tight joint therewith and the lip 21 preventing rain from entering between the panel and the ledge 19. The engagement of the lip 21 with the ledge 19 also securely holds 90 the panel and prevents rattling, and makes a neat finish. By having the guides 15 secured at one point only, they are free to bend and draw up sufficiently to permit the engagement of the lip 21 with the ledge 19. 95

For the purpose of preventing the panel 12 from striking the top of the door frame I have provided at either side of the frame a rubber bumper 28.

Having thus described my invention, what 100 I claim is:

1. In a window construction, the combination of a frame having grooves therein, the outer sides of which are bowed, substantially straight flexible guides in said grooves having 105 sash slots therein, a sash in said slots, and means at the lower end of said sash for securing the same in one of its positions with said guides fitting the bowed sides of said grooves.

2. In a window construction, the combination of a frame having grooves therein, the outer sides of which are bowed, substantially straight flexible guides secured at one end in said grooves and having sash slots therein, a sash in said slots, a ledge extending across said frame parallel with the sash, and means secured to the lower edge of the sash and adapted to engage said ledge to secure

the sash in one of its positions with the 10 guides fitting the bowed sides of the grooves.

In testimony whereof I affix my signature in presence of two witnesses.

JOSEPH F. O'BRIEN.
